UNITED STATES PATENT OFFICE

WALTER P. MURPHY, OF CHICAGO, ILLINOIS, ASSIGNOR TO P. H. MURPHY COMPANY, OF NEW KENSINGTON, PENNSYLVANIA, A CORPORATION OF PENNSYLVANIA

CAR ROOF

Application filed December 26, 1929. Serial No. 416,524.

My invention relates to metal car roofs and its principal object is to utilize the metal of the roof sheets more efficiently and to greater advantage than has been practicable heretofore. The invention consists principally in making the roof sheets with their marginal portions thicker than the intervening body portion throughout a width sufficient for forming seam or carline members. It also consists in the arrangements and combinations hereinafter described and claimed.

In the accompanying drawings, which form part of this specification and wherein like numerals refer to like parts wherever they occur,

Fig. 1 is a plan view of a part of a car roof embodying my invention,

Fig. 2 is a vertical cross-section of the roof on the line 2—2 of Fig. 1, said section being taken lengthwise through the body of the roof sheet,

Fig. 3 is a vertical cross-section of the roof on the line 3—3 of Fig. 1, said section being taken lengthwise through a seam,

Fig. 4 is a longitudinal cross-section of the roof on the off-set line 4—4 of Fig. 1,

Fig. 5 is a longitudinal section of the roof along the ridge as indicated by the line 5—5 of Fig. 1, and

Fig. 6 is a cross-sectional view of a roof sheet in the flat,

The roof illustrated in the drawings comprises Z-shaped side plates 1 and metal roof sheets 2 that extend from side plate to side plate and have their end portions turned down beyond the upstanding flanges of said side plates and riveted thereto. The margins of the roof sheets are formed into inverted channels 3. The channels of adjacent sheets overlap and are riveted together by means of vertically disposed rivets 4 to form hollow ribs or carlines 5. The inverted channels of the sheets and the hollow roof carlines

formed of such channels are of maximum depth at the ridge of the roof and taper towards the eaves; and the depth of the depending outer flange of each inverted channel increases from the ridge to the eaves. An angular bracket member 6 is interposed be-

tween the eaves corner portions of the sheets and the side plates.

Roofs of the general design above described are well known and render good service; but heretofore they have been made with sheets of even thickness throughout. That is, the practice heretofore has been to select and press up commercial roof sheets of a thickness that is uniform throughout and sufficient to take care of the maximum stress expected to be applied to the sheets in service, wherever the point of application of such stress may be.

One frequent result of such use of sheets of uniform thickness is that, in order to provide sufficient metal in the ribs to take care of the stress on the ribs, sheets are selected of greater thickness than is needed to take care of the expected stresses in the body of the sheet. Accordingly, the present invention discards sheets of uniform thickness and makes use of sheets whose marginal portions are of different thickness from that of the body portion, the thicknesses of the body and marginal portions being determined generally by the nature and amount of the work required of them.

Referring to Fig. 6, it is noted that my new roof sheet 2a is initially of rectangular form, with a parallel-sided body portion 7 bordered on each side by parallel-sided marginal portions 8 of greater thickness than the body portion. The lower surface of the sheet is preferably flush from side edge to side edge, the increase in thickness showing on the upper surface. These marginal portions are pressed into the inverted channel members above described or into ribs or flanges of other suitable designs.

One of the great advantages of my new roof sheet is that it affords greater freedom in designing roofs, especially as to the seam construction thereof, than is practicable when the seam or marginal portions and the body portions are of equal thickness. Likewise in comparison with a sheet of uniform thickness, my new sheet may be so designed that any surplus metal in the body portion above that required to take care of the expected stresses therein may be saved; or such

surplus metal may be added to the marginal portions with consequent increase in the strength and durability of the roof. Thus, for a given total weight of metal, it becomes practicable to concentrate a much larger proportion in the roof ribs or seams, where it is needed on account of the greater concentration therein of the stress. For instance, heretofore, in making riveted steel roofs of the general design shown in the accompanying drawings, sheets were frequently used of a uniform thickness of $\frac{3}{2}$ inch and a width of forty-eight inches. According to the present invention, a sheet of this same width may be made with about twelve inches along each side margin of a thickness of $\frac{1}{8}$ inch, and the intervening twenty-four inches or half of the entire width of the sheet made with a thickness of $\frac{1}{16}$ inch; in which case there would be the same total weight of metal as in the sheet of uniform thickness but the metal would be more effectively distributed for taking care of the stresses. Likewise, for a roof of equal strength, the new sheets may be made with a total weight of metal less than the total weight of a roof with sheets of uniform thickness. This saving in weight effects economy not only in the cost of the sheets, but reduces the total weight of the car and has the important advantage that such reduction of weight is made at the maximum distance above the center of gravity.

Under service conditions of a car roof, cinders and moisture are liable to lodge in the angle at the side of an upstanding seam and cause the sheet to be rusted out in this angle, while the sheet is still in excellent condition elsewhere. By making this angle portion thicker than the body portion, the effective life of the sheet is materially increased. Likewise there is a greater resistance to bending, and there is less danger of rivets tearing the sheets during the weaving of the car.

While I have illustrated my invention as embodied in a specific design using sheets with about one quarter of their width thickened along each side, it is to be understood that such design is only illustrative and that the invention is applicable to roofs of other designs.

What I claim is:

1. A car roof sheet having a parallel sided body portion and whose side marginal portions are undivided and of greater thickness than the body portion and are adapted to be shaped to form carline members.

2. A car roof sheet comprising a body portion and side marginal portions of greater thickness than the body portion, said marginal portions being of even thickness throughout their widths and struck up into seam forming members.

3. A car roof comprising metal roof sheets arranged side by side, the side marginal portions of said sheets being of even thickness

throughout their widths and thicker than the body portions thereof.

4. A car roof comprising metal roof sheets arranged side by side, the side marginal portions of said sheets being undivided and thicker than the body portions thereof and riveted together. 70

5. A car roof comprising metal roof sheets arranged side by side, the marginal portions of adjacent sheets being undivided and thicker than the body portions and shaped to form connecting seams. 75

6. A car roof comprising metal roof sheets whose side marginal portions are undivided and thicker than their body portions and shaped for seam forming engagement. 80

7. A car roof comprising metal roof sheets whose side marginal portions are of inverted channel shape and are thicker than their body portions, said marginal portions interlocking to form hollow carlines. 85

8. A car roof comprising metal roof sheets whose side marginal portions are of inverted channel shape and are thicker than their body portions, said marginal portions interlocking and riveted together to form hollow carlines. 90

9. A car roof comprising side plates and metal roof sheets secured to said plates and spanning the space between them, the side marginal portions of said sheets being undivided and thicker than their body portions and shaped to form connecting seams. 95

10. A car roof comprising side plates and metal roof sheets secured to said plates and spanning the space between them, the side marginal portions of said sheets being thicker than their body portions and pressed into inverted channel shape, said marginal portions interlocking and riveted together to form hollow carlines. 100

11. A car roof sheet comprising a body portion and side marginal portions of greater thickness than the body portion, each marginal portion being approximately half the width of the body portion and struck up into a seam forming member. 110

Signed at Chicago, Illinois, this 19th day of December, 1929.
